UNITED STATES PATENT OFFICE.

WELCOME WHITAKER, OF GOSHEN, INDIANA.

ROAD-CART.

SPECIFICATION forming part of Letters Patent No. 359,912, dated March 22, 1887.

Application filed May 26, 1886. Serial No. 203,291. (No model.)

To all whom it may concern:

Be it known that I, WELCOME WHITAKER, of Goshen, in the county of Elkhart and State of Indiana, have invented a new and Improved 5 Road-Cart, of which the following is a full, clear, and exact description.

The object of my invention is to provide a cheap and comfortable road-cart, and one that may be easily mounted, owing to the peculiar 10 arrangement of the seat-supporting bars.

Reference is to be had to the accompanying drawings, forming a part of this specification, in which similar figures of reference indicate corresponding parts in both the figures.

15 Figure 1 is a partly-sectional side view of a road-cart constructed in accordance with the terms of my invention, the section being taken on line *x x* of Fig. 2; and Fig. 2 is a sectional front view taken on line *y y* of Fig. 1.

20 Referring now to the general construction illustrated in the drawings, 10 is the axle. 11 11 are the wheels; 12, the thills, the rear ends of which are rigidly connected to the axle 10 in the manner indicated, the thills being braced 25 by rods 13, that are arranged as shown. The main cross-bar of the thills is shown at 14, and is rigidly connected to said thills in the position indicated, and braced by a curved bar, 15, which bar is fastened to the thills and 30 to the forward face of the cross-bar 14.

Beneath the cross-bar 14, I mount a spring, 20, said spring being held to the cross-bar by 35 clips 21. To each end of the spring there is secured an inverted-U stirrup, 22, and each 40 of these stirrups is provided with a shackle, 23, said shackles serving as the supports for the seat-carrying bars 25, the forward ends of said bars being pivotally connected to the under side of the thills through the medium of coupling-eyes 24 and shackles 26, said shackles being provided with two or more apertures, 2,

so that the seat 30, which is carried by the rear end of the bars 25, may be adjusted as desired. The bars 25 are practically straight from their forward ends to a point just behind the shackles 45 23—that is, to a point, 3. At this point 3 the bars are bent upward, to be again bent toward the rear at the point 4. Each of these bars carries a rod, 27, and the two rods serve as the supports for the cross slats 28, which constitute the bottom of the cart, and serve as a foot-rest for the occupant. Upon the axle 10 there is a step, 31.

Such being the general construction of the cart, it will be seen that it may be entered 55 without the necessity of climbing over any seat-supporting bars.

Although I have described my invention as applicable to carts having full springs, it will of course be understood that half-springs could 60 be used without departing from the spirit of my invention.

Having thus fully described my invention, what I claim as new, and desire to secure by Letters Patent, is—

65 In a road-cart, the combination, with the axle and thills rigidly secured thereto, of the cross-bar 14, secured on the upper side of the thills, the curved bar 15, secured to the thills and the said cross-bar, the seat-carrying bars 70 adjustably pivoted to the under side of the thills by the eyes 24 and shackles 26, the spring 20, secured to the under side of the bar 14, the stirrups 22 on the ends of the spring, and the shackles 23, for securing the stirrups to the seat-bars, substantially as herein shown and described.

75 WELCOME WHITAKER.
